(57) **CLAIM**

The ornamental design for a semiconductor device as shown and described.

DESCRIPTION

FIG. 1 is a front view of a semiconductor device showing our new design;

FIG. 2 is a rear elevational view thereof;

FIG. 3 is a left side view thereof;

FIG. 4 is a right view thereof;

FIG. 5 is a top plan view thereof; and,

FIG. 6 is a bottom plan view thereof.

The dash-dash broken lines in the drawings illustrate portions of the article that form no part of the claimed design. The dot-dash broken lines in the drawings illustrate the bounds of the claim and form no part of the claimed design.
